UNITED STATES PATENT OFFICE.

JAMES H. CLARK, OF CORYDON, IOWA.

DOOR OR GATE LATCH.

1,165,493.

Specification of Letters Patent. Patented Dec. 28, 1915.

Application filed September 2, 1915. Serial No. 48,696.

To all whom it may concern:

Be it known that I, JAMES H. CLARK, a citizen of the United States, residing at Corydon, in the county of Wayne and State of Iowa, have invented certain new and useful Improvements in Door or Gate Latches; and I do declare the following to be a full, clear, and exact description of the invention, such as will enable others skilled in the art to which it appertains to make and use the same.

This invention relates to new and useful improvements in latches, and more particularly to latches for use on sliding or swinging doors and gates, and the primary object of the invention is to provide a latch which embodies a fulcrumed lever, a stationary guide, and a latch link pivotally connected with the lever and adapted to slide and swing through the said guide whereby a quick, simple, and very efficient latch is formed.

A further object of the invention is to provide a device of this character which is simple and durable in construction, inexpensive to manufacture, and one which will be very efficient in operation.

With these and numerous other objects in view, my invention consists of certain novel features of construction, combination, and arrangement of parts which will be herein-after referred to and more particularly pointed out in the specification and claims.

In the accompanying drawings: Figure 1 is a side elevation of my improved latch showing it applied to use; Fig. 2 is a horizontal section taken on the line 2—2 of Fig. 1; Fig. 3 is a horizontal section taken on the line 3—3 of Fig. 1; Fig. 4 is a sectional view of the top, showing my improved latch adapted to hold the door when in open position; Fig. 5 is a side elevation of a slightly modified form of my improved latch showing the same in locked position; Fig. 6 is a side elevation showing the latch in unlocked position; Figs. 7 and 8 are horizontal sections taken on the lines 7—7 and 8—8 of Fig. 5, and Fig. 9 is a vertical section taken on the line 9—9 of Fig. 5.

In describing my invention, I shall refer to the accompanying drawings in which similar reference characters designate corresponding parts throughout the several views and in which the numeral 1 designates a door to which my improved latch may be applied, which is hinged to a frame 2 by hinges 3. This frame 2 which surrounds the

door is provided with a keeper 4 which is formed of a single piece of metal bent to form an eye 5 at one end, and the other portion being bent semi-circular as shown at 6 and terminating in a spur 7 which is adapted to be driven into the frame. This form shown in the accompanying drawings is merely one form of door to which the latch may be applied, as the same may be applied to any form of swinging door, or sliding doors or gates, without any reference to the particular form of gate or door employed.

Secured to the door 1 is a horizontally extending flat metal strip 8 which has one end 9 bent laterally and projecting from the said door, and having an aperture 10 therethrough. The end of this strip which is bent up is nearest the side of the door, and said bent end is adapted to form a guide for the latch as will be hereinafter more fully described. Adjacent the opposite end of the member 8 is an aperture 11 which alines with an opening through the gate 1, and a circular hollow shaft 12 is adapted to be positioned in the opening in said door, and projects therethrough at either end as shown at 13. An aperture 14 extends transversely through the projecting ends 13 of the shaft to receive the operating lever of this latch as will be hereinafter more fully described.

The link latch of this device which is designated by the numeral 15 consists of a rod having one end bent downwardly as shown at 16 to form a hook which is adapted to engage the keeper 4 when the latch is in locked position, and the other end of the said link latch is bent to form a circular loop 17. The lower end of the hook 16 of the link latch 15 is apertured as shown at 18 so that a car seal or pad lock for locking the door to securely seal the same, may be placed therethrough, as clearly shown in Fig. 1 of the drawings. The operating lever of this latch which is designated by the numeral 19 comprises a rod having one end bent laterally as shown at 20 and projecting through the circular loop 17 which is formed in the rear end of the link latch 15. The extremity of the lateral projection 20 on the end of the lever 19 is apertured to receive a cotter pin 21 which prevents the end 20 from slipping from the circular loop 17 when the parts are connected. This forms a pivotal connection between the front end of the operating lever 19 and the rear end of the link latch 15 of this device.

The operating lever 19 extends rearwardly through the transversely extending aperture 14 in the projecting end 13 of the hollow shaft 12 which extends through the door, and the said lever has its free end bent back upon itself as shown at 22 and spaced therefrom in parallel relation, to form an elongated loop handle for the said lever. The extremity 23 of the said handle is bent inwardly and is adapted to firmly fit into the open projecting end 13 of the shaft 12. When in this position, it is obvious that the operating lever 19 will be held firmly and securely through the rotatable shaft which extends through the door at a point intermediate of its ends, and a handle 22 will be formed on one of its ends, while the other will be pivotally connected with the rear end of the latch link 15. The opposite end of the hollow shaft 12 which projects through the door 1 has formed thereon an elongated handle loop 24 which is formed substantially the same as the handle loop 22 on the lever 19 to which the link latch 15 is attached. This handle 24 on the opposite side of the door projects radially in the opposite direction from the rotatable shaft 12 the purpose of which is obvious, and it will be readily seen that by the provision of this shaft with the handle at each of its projecting ends, this latch may be operated from either side of the gate or door.

When the parts of this device are assembled as shown in Fig. 1 of the drawing, which shows the latch in locked position, to release the same it is only necessary to grasp the elongated loop handle 22 at the free end of the operating lever 19 and move the same upwardly. This, on account of the pivotal connection between the opposite end of the lever and the rear end of the link latch, will draw the rear end of the link latch downwardly and inwardly, thereby swinging the opposite end on which the hook is formed, upwardly and inwardly from out of engagement with the keeper 4. This will disengage the latch from the keeper and allow the door to be swung as desired. When it is desired to latch the said door when the same is closed, it is only necessary to swing the lever 19 from the substantially vertical position which it assumes when not in operative position, downward to horizontal alignment with the link latch 15, whereby the hooked end of the same will be brought into engagement with the keeper 4 on the frame of the door to securely latch the said door.

One of the essential features of this device is the projecting apertured end 9 on the horizontally extending metal strip 8, which forms a guide so that the link latch 15 is adapted to slide and swing therethrough upon movement of the lever. The aperture 10 in the said projecting end is of suffi-

cient size to allow a free and easy movement of the shank of said link latch therethrough so that upon the slightest movement of the lever, the same will freely slide or swing through the same.

70

Another essential feature of my invention is the provision of the particular form of lever which by this formation forms at one end an integral elongated loop-shaped handle. This handle and the way it is secured to the transversely extending shaft that rotates in the door forms a novel and very efficient operating lever for a device of this character.

75

In Figs. 5 to 9 inclusive is shown a slightly modified form of my invention, attached to a door 25 which is hinged to a frame 26 by means of any ordinary form of hinges 27. This door frame and hinges is substantially the same as that type to which the other form of my invention is applied, and corresponds to the same. The frame 26 which surrounds the door is provided with a keeper 28. This keeper 28 comprises a plate 29 secured firmly to the said frame, and having projecting therefrom a horizontally disposed staple 30 and a pair of vertically disposed staples 31 and 32 disposed beneath the horizontally disposed staple, and positioned in parallel spaced relation to one another. The horizontally disposed staple 30 is adapted to receive the hook of the latch link, as will be hereinafter more fully described. The object of the parallel vertical staples 31 and 32 is so that when the latch is in locked position and it is desired to permanently lock the same, a padlock 33 may be positioned therethrough, so as to accomplish the aforesaid purpose in the manner clearly shown in Fig. 5 of the drawings. If desired, a seal may be positioned therethrough in place of the padlock.

My improved form of modified latch comprises a base plate 34 which in this instance is shown as being substantially oval-shaped and firmly and securely held into engagement with the door by means of any desired form of fasteners for instance as shown at 35. This base plate 34 has projecting outwardly from a point adjacent one end of the same, a headed bolt 36 for a purpose to be hereinafter more fully described. The link latch 37 of this modified form comprises a flat elongated strip having a longitudinally extending slot 38 disposed therethrough, which is adapted to receive the bolt 36 of the base plate 34, and has a slideable and swinging engagement therewith. The outer end of the link latch 37 has projecting downwardly therefrom at right angles to the same a hook 39 having adjacent its outer end an elongated slot 40 the purpose of which is obvious. Fulcrumed to a point adjacent the opposite end of the base plate 34 is a lever 41 which is pivotally mounted

with respect thereto as shown at 42. This lever 41 has its rear end enlarged as shown at 43 so that the same may be easily grasped when it is desired to operate this latch. The 5 forward end of the lever 41 is pivotally engaged with the rear end of the link latch 37 as designated by the numeral 44. When the parts of this modification are in position as above described, the operation of the same 10 is substantially the same as the operation of the previously described preferred form of latch. It is only necessary to move the lever 41 upwardly, when the parts are assembled as shown in Fig. 5 of the drawings to cause 15 the link latch 37 to move rearwardly and downwardly, thereby lifting the hook 39 from out of engagement with the keeper 28. This movement of the link latch 37 is caused by the slotted engagement of the same with 20 the headed bolt 36 secured to the base plate 34. The keeper 28 which is shown in this modified form may be applied to the preferred form of this invention hereinbefore described.

25 From the foregoing description of the construction of my improved latch, the manner of applying the same to use, and the operation thereof will be readily understood, and it will be seen that I have provided a 30 simple, inexpensive, and efficient means for carrying out the objects of this invention.

I claim as my invention:

1. A latch of the character described comprising a stationary guide, a link latch 35 adapted for sliding and swinging engagement with said guide, a hook on the forward end of said latch, and a lever fulcrumed intermediate of its ends pivotally connected at one end with the rear end of 40 said latch, whereby when the lever and link are in horizontal alinement the hook on the latch will be positioned in a keeper.

2. A latch of the character described comprising a stationary horizontally extending 45 metal strip having a laterally projecting apertured end, a link latch projecting through the aperture in said guide and adapted to slide and swing through the same, a hook on the forward end of said latch, and a lever fulcrumed intermediate of 50 its ends pivotally connected at one end to the rear end of said latch, whereby when the lever and link are moved into horizontal alinement, the hook on the latch will be 55 positioned in the keeper.

3. A latch of the character described comprising a stationary horizontally extending metal strip having a laterally projecting apertured end, a link projecting through the 60 aperture in said guide and adapted to slide and swing through the same, the forward end of said latch being bent downwardly to

form a hook, a loop formed at the rear end of the same, a lever fulcrumed intermediate of its ends and pivotally connected at one 65 end to the rear end of said latch, and a handle formed on the other end of said lever.

4. A latch of the character described comprising a stationary horizontally extending 70 metal strip having a laterally projecting apertured end, a link projecting through the aperture in said guide and adapted to slide and swing through the same, the forward end of said latch being 75 bent downwardly to form a hook, said hook having an aperture adjacent its lower end, a loop formed at the rear end of said latch, a shaft rotatably mounted on one end in the guide and having an aperture therethrough, 80 a lever positioned through the aperture in said bolt and securely held therein intermediate its ends, said lever being laterally bent at one end to pivotally engage the loop in the rear of the latch, and the free end of 85 the lever being bent upon itself to form an elongated loop handle.

5. The combination with a door, a rotatable shaft having a transverse opening therethrough, a rod extending through said 90 opening and having one end bent upon itself to form an elongated loop, and the other end of said rod connected with the latch member.

6. The combination with a door, a shaft 95 rotatably mounted thereon, projecting laterally therefrom, the projecting end of said shaft being hollow and having a transverse opening therethrough, a rod extending through said opening and having one end 100 bent upon itself and the extremity thereof positioned in the open end of the shaft, and the other end of said rod pivotally connected with a latch member.

7. A latch of the character described comprising a stationary guide, a link latch adapted for sliding and swinging engagement with said guide, a hook on the forward end of said latch, a keeper comprising a horizontally disposed hook receiving staple 110 and a pair of parallel vertically disposed staples disposed below the same, and a lever fulcrumed intermediate its ends pivotally connected at one end with the rear end of 115 said latch, whereby when the lever and link are in horizontal alinement the hook on the latch will be positioned in the keeper.

In testimony whereof I have hereunto set my hand in presence of two subscribing witnesses.

JAMES H. CLARK.
